UNITED STATES PATENT OFFICE.

ZENAS P. CANDEE, OF WATERBURY, CONNECTICUT, ASSIGNOR TO THE WATERBURY FARREL FOUNDRY AND MACHINE COMPANY, OF WATERBURY, CONNECTICUT, A CORPORATION OF CONNECTICUT.

TRANSFER MECHANISM.

1,426,039.

Specification of Letters Patent. Patented Aug. 15, 1922.

Application filed May 20, 1920. Serial No. 383,003.

To all whom it may concern:

Be it known that I, ZENAS P. CANDEE, a citizen of the United States, residing at Waterbury, in the county of New Haven and State of Connecticut, have invented certain new and useful Improvements in Transfer Mechanisms, of which the following is a specification, reference being had therein to the accompanying drawings.

10 The invention herein described relates to new and improved transfer mechanism and more particularly to such mechanisms as are used on machines for transferring articles from one station to another either for operations thereon or for other purposes.

It is the object of this invention, among other things, to provide means whereby a transfer mechanism of substantial length may be constructed and operated so that the 20 relative parts thereof move in unison and in substantially parallel lines, such mechanism being so arranged that the liability of the ends of said transfer mechanism getting out of alignment is reduced to the absolute minimum, in fact eliminated.

To these, and other ends, my invention consists in the transfer mechanism having certain details of construction and combinations of parts as will be hereinafter 30 described and more particularly pointed out in the claims.

Referring to the drawings in which like numerals of reference designate like parts in the several figures,

35 Figure 1 is a plan view of one form of my improved mechanism with some of the adjacent parts shown in connection therewith.

Figure 2 is a fragmentary elevation thereof.

40 Figure 3 is an enlarged fragmentary plan view of a portion of the link mechanism; and

Figure 4 is an enlarged end elevation with the parts shown in section being taken substantially upon line 4—4 of Figure 3.

I have illustrated my invention as applied to a machine having transfer mechanism with seven pairs of transfer fingers connected therewith, for the purpose of transferring 50 successively a single article from a receiving station to a plurality of tools, one after another and then to a discharge station.

This particular application of my mecha-

nism is merely shown for the purpose of illustration and within my invention is not limited thereto.

Heretofore in mechanism of this character the element carrying the transfer fingers has usually been operated from a single shaft, substantially parallel with said element, having one or more cams thereon, these generally being located adjacent to the ends of the carrier mechanism.

In practice it has been found that with some classes of work this shaft is liable to spring under the operating strain so that the cams although timed in unison do not so act on account of this springing action of the shaft, the result being that the carrier fingers connected with the carrier mechanism at opposite ends thereof, do not operate in a predetermined manner, some having a tight grip upon the article and the other a loose grip and still others possibly no grip at all. Obviously such action makes the mechanism uncertain and unreliable and is detrimental to the successful operation of the tools with which the transfer mechanism is associated.

With my improved device I so arrange 80 the means for actuating the mechanisms that the transfer fingers move in and out toward and away from each other with certainty and in unison with the possibility of springing entirely eliminated and the objections above referred to entirely obviated.

85 In the drawings 10 represents a portion of the body of a machine to which my improved mechanism is applied; 11 is a bolster plate fixed thereto; 12 is a bracket secured to one end of said bolster plate and within which is journaled the shaft 13 having thereon a cam 14 for imparting a longitudinal movement to the transfer mechanism and a cam 15 for imparting an in and out movement thereto.

The reference numerals 16 and 17 designate the companion members or carrier plates, the latter being the front carrier plate and the former the rear carrier plate. 100 These plates are connected at one end by the bar 18 which is fixed to the carrier slide 19. Said plates have a sliding movement on the bar 18 toward and away from each other. This carrier slide 19 is provided 105 with two cam rolls 20 which contact with

the face of the cam 14 whereby a reciprocatory movement is given the slide upon the bracket 12.

An adjustable stop 21 threaded into the support 22 fixed to the bracket 12 provides means for limiting the movement of said bracket in one direction.

In each of these carrier plates 16 and 17 is mounted a plurality of transfer fingers 23, these being arranged in pairs as shown and preferably adjustable. The design and construction of these fingers and the method of attachment to the bars constitute no part of this invention and are therefore not described more in detail, except that as shown clamps 24 are provided, within which finger holders 25 are secured having the fingers 23 connected therewith. In the bolsters 26 are fixed the tool holders 27. The design, construction and method of holding these tool holders is not material to my invention and are therefore not described more in detail.

Fixed in the bolster plate 11 are the studs 28 preferably 4 in number, but more may be used if the transfer mechanism is excessively long, or the work required thereby is such as to demand it.

Rotatably mounted upon two of the studs 28 are the bell cranks 29 and upon the opposite two are the rock levers 30. The bell cranks and rock levers are arranged in pairs and are connected by rods 31 and the bell cranks are connected by the rod 32. The connections between the rods 31 and the bell cranks 29 and levers 30 and the rod 32 with the bell cranks 29 are pivotal so that they may have relative movement one with the other.

Rotatably mounted upon a stud 33, fixed in the bracket 12, is a rock lever 34, having a cam roll 35 upon one end thereof, which lies within the cam groove 36 in the in and out cam 15 and is connected with the rod 32 by the link 37. This latter is accomplished by means of the plates 38 secured to the rod 32 and the pintle 39. By this construction the removal of the pintle 39 and one of the plates 38 provides means for disengaging all of the mechanism associated with the bracket 12 from the parts associated with the bolster plates which permits economy in machining of the parts and their ready assembly and dismantling.

As the carrier plates 16 and 17 have no fixed engagement with the bar 18, and only a sliding connection therewith, this also facilitates the removal of the bracket 12 as above mentioned. In each of the bell cranks 29 and the levers 30 are the studs 40 upon which are mounted the swivel blocks 41, to which are secured the caps 42 and within which are slidably mounted the carrier plates 16 and 17 which have an endwise movement therein; and during the movement

of said carrier plates toward and away from each other the swivel blocks are movable upon their pivot mounting.

The rotation of the in and out cam 15 imparts a rocking movement to the rock lever 34 and through the link 37 and rod 32 a rocking movement is imparted to the bell cranks 29 and through the rods 31 this motion is transmitted to the rock levers 30. As the studs 40 in the bell cranks 29 and rock levers 30 are upon opposite sides of the centers of the studs 28 a parallel movement of the carrier plates 16 and 17 toward and away from each other is thereby imparted. Each end of each carrier plate being now actuated through mechanism wherein there is no possibility of warping or springing, an absolute parallel movement and in unison of all portions of the carrier plates is obtained.

Minor changes and alterations may be made within my invention aside from those herein suggested and I would therefore have it understood that I do not limit myself to the exact construction herein shown and described but claim all that falls fairly within the spirit and scope of the appended claims.

Having described my invention what I claim as new and desire to secure by Letters Patent, is:

1. A transfer mechanism having companion members, means having connection with both of said members at points relatively distant from each other for positively moving said members toward and away from each other, and means for imparting an endwise movement to said members while held in one of their relative positions.

2. A transfer mechanism having companion members, means comprising rock members connected to each other so as to move as a unit, said rock members being located at points relatively distant from each other for moving said companion members toward and away from each other, means for actuating said rock members in unison, and means for imparting an endwise movement to said members while held in one of their relative positions.

3. A transfer mechanism having rock members arranged in pairs, each member in each pair being operatively connected with the other member of the pair, and one member in each pair having an operative engagement with one member in another pair; a companion member associated with one of each of said pairs of rock members whereby the movement of said rock members will cause a movement of the companion members toward and away from each other, and means for imparting an endwise movement to said members while held in one of their relative positions.

4. A transfer mechanism having companion members, a fixed part, a plurality of rock members pivotally connected with said

fixed part and arranged in pairs, a link connection between the rock members of each pair, a connection between one of each of said pairs of rock members with one of the 5 rock members of another pair, means for slidably connecting one of said companion members with one of each of said pairs of rock members, means for actuating all of said rock members, whereby movement is 10 transmitted to said companion members toward and away from each other, and means for imparting an endwise movement to said members while held in one of their relative positions.

15 5. A transfer mechanism having companion members, rock members connected with a fixed part and arranged so that one rock member is adjacent to each end of each of said companion members, means for operatively connecting said rock members in pairs, and said pairs of rock members with each other, and means for actuating said rock members comprising in part a positively actuated connection, and means for separably 20 securing said connection to said rock members.

30 6. A transfer mechanism having companion members, a plurality of rock members pivotally connected with a fixed part and arranged in pairs, a connection between the rock members of each pair, means for slidably connecting one of each of said pairs of rock members with one of said companion members, and the other of each of 35 said pairs of rock members with the other companion member, a connection between one of each of said pairs of rock members with one of the rock members in another pair; means for actuating all of said rock 40 members, whereby movement is transmitted to said companion members toward and away from each other, and means for imparting an endwise movement to said members while held in one of their relative 45 positions.

50 7. A transfer mechanism having companion members, a plurality of rock mounted members, a swivel block on each of said rock members, forming an operative connection between said rock member and said companion members, means for operatively connecting all of said rock members so that movement thereof will cause said companion members to move toward and away 55 from each other, and means for imparting an endwise movement to said members while held in one of their relative positions.

60 8. In a transfer mechanism, wherein the carrier elements have movement toward and away from each other and at an angle thereto, the combination with companion members; of means for causing the latter to move toward and away from each other in parallel lines, comprising mechanism having a swivel engagement with a part fixed 65

in relation to said companion members, and connected with said companion members at each end thereof, and mechanism for positively actuating said means in unison, and means for imparting an endwise movement 70 to said members while held in one of their relative positions.

9. A transfer mechanism having a fixed part, rock members pivotally connected therewith at points thereon corresponding 75 with the corners of a parallelogrammatic figure, a link connection between the two rock members at the opposite ends of said fixed member, a link connection between the two rock members on one side of said 80 fixed member, companion members, each of which has a sliding and swivel connection with two of said rock members, means for actuating said rock members whereby movement is imparted to said companion members toward and away from each other, and means for imparting an endwise movement 85 to said members while held in one of their relative positions.

10. A transfer mechanism having rock 90 members pivotally connected with a fixed part at points thereon corresponding with the corners of a parallelogrammatic figure, a link connection between the two rock members at the opposite ends of said fixed 95 member, a link connection between the two rock members on one side of said fixed member, companion members, each having a sliding and swivel connection with two of said rock members, means for actuating 100 said rock members to impart movement to said companion members toward and away from each other, comprising a rock lever, means for actuating said rock lever, a connection between said rock lever and said 105 rock members; all of said latter mechanism being so connected with said fixed part and said companion members as to be readily disengaged therefrom.

11. A transfer mechanism having a 110 bracket connected with a fixed part, companion members, rock members pivotally connected with said fixed part and having an operative engagement with said companion members, means, connected with 115 said bracket for imparting movement to said rock members, whereby said companion members may be moved toward and away from each other, means for imparting movement to said companion members in a direction parallel to their length and independent of their movement toward and away from each other while in one of their relative positions upon said rock members, and means for forming a separable connection 120 between the mechanism connected with said bracket and those associated with said fixed part.

12. A transfer mechanism having a bracket connected with a fixed part, a slide 125

upon said bracket, means connected with said bracket for imparting movement to said slide, companion members having an operative engagement with said slide, means connected with said bracket and transmitting motion through said rock members to said companion members which are caused to move toward and away from each other, and a connection between said

slide and companion members and said rock members, whereby said bracket and its associated parts may be readily removed without disarranging the relative positions of the said companion members and rock members.

In testimony whereof, I have hereunto affixed my signature.

ZENAS P. CANDEE.
